UNITED STATES PATENT OFFICE

2,193,995

LIPSTICK DEVICE

James L. Younghusband, Chicago, Ill.

Application October 24, 1938, Serial No. 236,608

1 Claim. (Cl. 206—56)

My invention relates to a case for holding lipstick having means for projecting the lipstick for use and retracting it within the case for storage during nonuse.

5 Among the objects of my invention is to provide simple manually operable means for the quick projection and retraction of the lipstick, said means occupying small space not otherwise used in the case, and such other objects, advantages 10 and capabilities as will later more fully appear and which are inherently possessed by my invention.

15 While I have shown in the accompanying drawing a preferred embodiment of my invention, yet I wish it understood that the same is susceptible of modification and change without departing from the spirit of my invention.

20 Referring to the drawing Fig. 1 is a front elevation of the exterior of my lipstick device; Fig. 2 is a sectional view on line 2—2 of Fig. 1; Fig. 3 is a sectional view on line 3—3 of Fig. 1; Fig. 4 is a sectional view on line 4—4 of Fig. 1 and Fig. 5 is a sectional view on line 5—5 of Fig. 4.

25 One embodiment selected to illustrate my invention comprises a hollow body member 10 having side walls 11 and open at the top and bottom. Positioned and movable within said body member 10 is a cup 20 adapted to hold lipstick 27 or the like.

30 Adjacent the upper portion of the body member 10 is a bearing 39, and adjacent the lower portion of the body member 10 is a turnable member or spool 40.

35 A cord, chain or continuous member 41 extends as a loop from the bearing member 39 to the turnable member 40. The continuous member 41 is attached to the cup 20.

40 One form of my bearing member 39 shown in Fig. 2 is a rod 42 preferably positioned across a corner of the interior of the body member 10 and attached to two of the side walls 11. Rod 42 may be either fixed or rotatably attached to the side walls 11.

45 The turnable member 40 is rotatably supported by oppositely disposed side walls 11, or the corners of the same when extending diagonally across the body member 10. Said turnable member 40 extends through the wall of the body member 10 on one end, and attached to said end is a wheel 24 manually operable from the exterior of the device.

5 The continuous member 41 is attached to the cup 20 by any suitable means. The cord 41 may pass through openings in the cup 20 or an extension 21 of the cup and be bent, looped or knotted so that when the cord 41 is moved, the cord will also move the cup. Any other suitable means for attaching the continuous member 41 to the cup 20 may be used without departing from the spirit of my invention.

10 When the wheel 24 is turned the spool 40 is also turned. When the wheel 24 is turned in one direction the spool 40 moves the loop 41 so as to pull the cup 20 upwardly so that the lipstick 27 in the cup may project from the top of the body member 10 and be used. When the wheel 24 is 15 turned in the opposite direction the spool 40 turns and moves the loop 41 so as to pull the cap 20 with its lipstick 27 back into the body member 10 for storage during nonuse.

15 A bottom closure 34 is fitted by friction grip 20 within a depression 35 in the lower outer ends of the side walls 11 of body member 10. A cap 28 is formed to fit over the open top of body member 10 by friction grip within depression 35 at the upper 25 ends of the side walls 11.

Having thus described my invention, I claim:

20 A lipstick device comprising a hollow substantially rectangular tube, a cup adapted to hold lipstick positioned within said tube, a rod extending across a corner of the upper portion of the interior of said tube and attached to contiguous side walls, a turnable member extending through said tube and rotatably supported by opposite side walls adjacent the lower portion of said tube, a loop 30 attached to said cup and extending from and above said rod downwardly along one of the corners of the interior of the tube to and below said turnable member, a wheel manually operable from the exterior of the tube and attached to the turnable member, said wheel adapted upon being turned in one direction to turn the turnable member and in turn to move the loop so as to project the cup with its lipstick to substantially 35 the top of the tube, and upon being turned in the opposite direction to turn the turnable member and move the loop so as to pull the cup and its lipstick within the tube, and closures for the open top and bottom of said tube.

JAMES L. YOUNGHUSBAND.
